W. SACHS.
TRASH RECEPTACLE.
APPLICATION FILED OCT. 14, 1919.

1,338,400.

Patented Apr. 27, 1920.

UNITED STATES PATENT OFFICE.

WALTER SACHS, OF PETERSBURG, VIRGINIA.

TRASH-RECEPTACLE.

1,338,400.

Specification of Letters Patent. Patented Apr. 27, 1920.

Application filed October 14, 1919. Serial No. 330,644.

To all whom it may concern:

Be it known that I, WALTER SACHS, a citizen of the United States, residing at Petersburg, in the county of Dinwiddie and State 5 of Virginia, have invented a new and useful Trash-Receptacle, of which the following is a specification.

This invention relates to new and useful improvements in receptacles, and more particularly to trash receptacles, to be located 10 on street corners, or other public places, to receive and contain papers and trash usually discarded on the public streets.

The primary object of the invention is 15 to provide a device of this character including a main receptacle having means for directing the trash or refuse deposited therein, to a removable receptacle supported within the main receptacle.

20 A further object of the invention is to provide means within the main receptacle for properly supporting the removable receptacle within the main receptacle, whereby the same will be held against displacement therein, and at the same time will be 25 supported to receive material deposited in the main receptacle without the possibility of the material falling between the walls of the removable receptacle, and the main receptacle.

With the foregoing and other objects in view which will appear as the description 30 proceeds, the invention resides in the combination and arrangement of parts and in the details of construction hereinafter described and claimed, it being understood 35 that changes in the precise embodiment of the invention herein disclosed, may be made within the scope of what is claimed, without departing from the spirit of the invention.

40 Referring to the drawing:—

Figure 1 illustrates a front elevational view of a trash receptacle constructed in accordance with the present invention, and

45 Fig. 2 illustrates a longitudinal sectional view through the same.

Referring to the drawing in detail, the receptacle is shown as including a main or body portion 5 and an upper or top portion 6, the body portion and top portion having coöoperating flanges 7, apertured as 50 at 8 to receive the securing bolts 9, whereby the top and bottom portions of the receptacle are secured together.

55 The body portion 5, is provided with a bottom 10, the side walls of the body por-

tion 5 extending downwardly and terminating at points below the plane of the lower side of the bottom 10, to provide flanges to coöperate with the upper edges 60 of the supporting legs 11, which as shown, are secured thereto by means of the bolts 12, the supporting legs being preferably formed of sheet metal bent to provide right angle surfaces to exactly fit within the respective corners formed by the flanges of the side walls of the body 5.

This bottom 10, is provided with upwardly extending flanges 13, spaced from the inner side walls of the body portion 5, 70 and provide a receiving compartment for receiving the removable receptacle 14, which is in the form of a sheet metal box, the side walls of which extend upwardly terminating at points directly below the lower edges 75 of the funnel 15.

The funnel 15, includes side walls 16 and end walls 17, which extend downwardly at an angle, the upper edges of the funnel 15 being secured to the inner walls of the 80 body 5, by any suitable means, the same being disposed however, substantially intermediate the length of the body 5.

An opening 18, is provided in the lower rear wall of the body 5, and is closed by 85 the door 19, hinged to the body 5, as at 20, so that the same swings downwardly, thus providing a door which is normally held in a closed position, a latch member 21 being pivotally connected to one of the lower 90 flanges of the side walls of the body 5, to move into coöperative relation with the door 19, for locking the same in its closed position, the handle 22, being provided to permit the door to be easily operated by an 95 attendant, in the event that it becomes necessary to empty the receptacle or container 14.

Disposed on the inner surface of the door 19, are the flanges 23, which flanges are of a length to engage the container 14, when 100 the door is in a closed position, to force the container 14 into engagement with the flanges 13, provided on the bottom 10, thus locking the container 14 within the body of the receptacle against displacement, in the 105 event that the trash receptacle were knocked down or blown over.

An opening 24 is provided in the top portion 6, which opening is controlled by the closure 25 hinged thereto from its upper 110 edge as at 26, so that the door will normally close, under its weight.

From the foregoing it will be seen that refuse deposited within the receptacle, falls downward contacting with the funnel 15, from where it is directed to the container 14, the funnel 15 being supported in such relation with the container 14, that the material will not fall between the side walls of the container 14, and the inner walls of the body 5, thus providing an absolutely sanitary receptacle, since when the container 14 is removed and cleaned, all the refuse within the trash receptacle has been removed.

It might be further stated that due to the spaced-relation between the container 14 and the inner walls of the body 5, the trash receptacle is efficiently ventilated, air passing around the container 14 and upwardly within the trash receptacle between the upper edges of the container 14, and funnel 15.

Having thus described the invention, what is claimed is:—

1. In a receptacle, a funnel shaped member supported within the receptacle substantially intermediate the length thereof, said funnel shaped member dividing the receptacle into upper and lower compartments, cooperating flanges extending upwardly from the bottom of the lower compartment, said flanges being disposed in spaced relation with the side walls of the lower compartment, the flanges being disposed directly

under the funnel shaped member, a removable receptacle adapted to fit between the flanges, a hinged door forming a part of one wall of the receptacle, and means on the door for contacting with the removable receptacle for holding the removable receptacle under the funnel shaped member.

2. In a receptacle, a funnel shaped member disposed within the receptacle and dividing the receptacle into an upper and lower compartment, flanges extending upwardly from the bottom of the lower compartment, a removable receptacle adapted to be embraced by the flanges for supporting the removable receptacle in a position directly under the funnel shaped member, a pivoted closure forming a part of one of the walls of the first mentioned receptacle, and a plurality of flanges extending laterally from the pivoted closure and contacting with the removable receptacle when the closure is in its closed position, said flanges adapted to support the removable receptacle against displacement within the lower compartment.

In testimony that I claim the foregoing as my own I have hereto affixed my signature in the presence of two witnesses.

WALTER SACHS.
